Primary Examiner — Mary Shannon Malley(74) *Attorney, Agent, or Firm* — Banner & Witcoff, Ltd.(57) **CLAIM**

The ornamental design for a backpack, as shown and described.

DESCRIPTION

FIG. 1 is a top, front, left perspective view of a backpack showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines within the shaded areas depict stitching that forms no part of the claimed design. The broken lines within the unshaded area of FIG. 7 show features that form no part of the claimed design.

1 Claim, 7 Drawing Sheets(56)
